GRINDING MACHINE

Walter D. Archea, Cincinnati, Ohio, assignor to
Cincinnati Grinders Incorporated, Cincinnati,
Ohio, a corporation of Ohio

Application January 12, 1933, Serial No. 351,879

15 Claims. (Cl. 51—105)

This invention relates to improvements in machine tools and especially to improvements in grinding machines for grinding surfaces of revolution on relatively small articles that are difficult to chuck or support during the grinding operation.

An object of this invention is the provision of a grinding machine that may be operated either manually or semiautomatically for expeditiously producing such work pieces.

Another object of the invention is the provision of a grinding machine for automatically centering and clamping the work in position prior to the presentation thereof to the grinding wheel and subsequently withdrawing the work from the grinding wheel, releasing and ejecting same from the machine.

A further object of this invention is the provision of a simple improved machine for accomplishing the above objects.

Other objects and advantages of the present invention should be readily apparent by reference to the following specification considered in conjunction with the accompanying drawings and it is to be understood that any modifications may be made in the exact structural details there shown and described, within the scope of the appended claims, without departing from or exceeding the spirit of the invention.

In the drawings:

Figure 1 is a front elevational view of the grinding machine embodying the improvements of this invention.

Figure 2 is an end elevation of the machine shown in Figure 1, as seen from the right hand end thereof, certain parts being removed.

Figure 3 is a transverse sectional view as seen from line 3—3 on Figure 1.

Figure 4 is a vertical sectional view on line 4—4 of Figure 1.

Figure 5 is a longitudinal sectional view as seen from line 5—5 on Figure 3.

Figure 6 is a fragmentary elevational view of the parts of the machine shown in Figure 1 and illustrating a modification.

Figure 7 is a transverse sectional view taken on line 7—7 of Figure 6.

Figure 8 is a sectional view taken on line 8—8 of Figure 6.

Figure 9 is a sectional view taken on line 9—9 of Figure 8.

Figure 10 is a sectional view taken on line 10—10 of Figure 9.

Figure 11 is an enlarged sectional view taken on line 11—11 of Figure 7.

Throughout the several views of the drawings similar reference characters are employed to denote the same or similar parts.

This invention, as noted above, pertains particularly to a machine for expeditiously pro-

ducing an exterior ground surface of revolution on hollow or cylindrical work pieces which are relatively difficult to support during the grinding operation, or which require an unusual amount of time to properly mount on a mandrel, 65 arbor or the like. In general the machine comprises a work receiving member, such as a spindle nose or work arbor on which the work is held by suitable holding means and subsequently presented to the grinding wheel. The work holding means is tied in with the feeding or presentation means so that a sequence of operation is had for first properly centering, securing and rotating the work prior to the presentation thereof to the grinding wheel and subsequently retracting the same from the work and finally releasing, stopping the rotation, and ejecting the work from the machine.

Specifically, the grinding machine comprises a bed 15 from the upper surface of which rises 80 a pedestal bearing supporting a spindle 16 to which is secured the grinding wheel 17. The spindle 16 and wheel 17 are adapted to be rotated at a relatively high grinding rate of speed and the grinding wheel is partially enclosed 85 within a hood or guard 18 usual with machines of this character for confining the coolant employed therewith. The guard 18 has projecting therefrom a ledge or shelf 19 supporting a slide 20 carrying the truing mechanism 21 adapted 90 to true the operative face of the grinding wheel 17.

The bed 15 is further provided on its upper surface with a dove-tailed guide 22 received in a correspondingly shaped guideway 23 formed on 95 the under side of the work supporting slide 24. In order to shift the housing or slide 24 there is provided, see Figures 1 and 5, an adjusting screw 25 having its threaded end received in a nut 26 rotatably journaled in a bearing provided by the housing 24. The outer end of the screw 25 extends through and beyond a bearing bracket 27 and to the projecting end of which is secured a hand or pilot wheel 28 whereby the said screw is rotated for effecting 100 major adjustments of the housing or slide 24. Keyed or otherwise secured to the nut 26 is a barrel cam 29 having formed therein a cam track receiving the head of a guide pin 30 carried by cup member 31 screwed or otherwise 105 secured to the housing 24. Further secured to the nut 26 is a manually operable infeed lever 32 which effects the cycle of the machine when same is to be manually operated.

As seen in Figure 3, the housing or slide 24 has 110 formed integral therewith a pair of bearings 33 and 34 in which is secured the usual tapered spindle bearing bushings 35 and 36 for the work supporting and rotating spindle 37. The spindle 37 between the bearing bushings 35 and 36 is 115 120

provided with a sprocket 38 about which is trained a sprocket chain 39, see Figure 2, in turn extending about the sprocket 40 secured to a shaft 41 projecting from the rear side of the bed near the lower edge thereof. The shaft 41, interiorly of the bed, is geared or otherwise coupled to suitable sliding gears within the variable speed box 42 secured to the right hand end of the bed 15. Suitable shift levers 43 being provided for actuating the sliding gears and effecting and controlling the rate of rotation of the shaft 41 and consequently the spindle 37. The outer end of the spindle 37, see Figure 3, has secured to it in any desirable manner a chuck or sleeve 44 terminating in a stub arbor 45 received in a finished bore in the work piece 46. The work piece 46 is held on the chuck 44 by a holding or clamping head 47 in which is disposed the anti-friction bearings 48 for the end plate 49, which actually contacts with the free end of the work. In other words, the work is held or secured to the chuck for rotation therewith by clamping same between the plate 49 and a shoulder 50 formed on the chuck head 44.

The clamp head 47 is integral with a lever 51 loosely journaled on a shaft 52 rotatably mounted in bearings 53 provided by the housing or slide 24. Secured in any desirable manner to one end of the shaft 52, adjacent the arm 51, is a pressure finger 54 having mounted in its free end a spring pressed plunger 55 that engages with a shoulder 56 on the lever 51 for yieldably actuating the same in a clockwise direction into engagement with the work 46. The shaft 52 has secured to its other end a trigger 57 that lies against the flat surface 58 of the axially shiftable rack bar 59. The bar 59 has formed therein at the end of the flat 58 a notch 60 to provide a shoulder 61 that engages with the trigger 57 for rotating or oscillating same together with the shaft 52 in a counterclockwise direction. The oscillation of these parts in said counterclockwise direction raises the pressure finger 54 and through the pin and slot connection 62 effects the elevation of the arm 51 and thereby freeing the work so that it may be subsequently ejected from the chuck 44.

The rack bar 59 is axially shiftable through bearings 63 provided by the housing or slide 24, interiorly thereof, and has formed near its lower end rack teeth 64 intermeshed with the teeth on pinion 65. The pinion 65 is keyed or otherwise secured to the inner end of the nut 26 and rotates with said nut during the rotation thereof by means of the manual infeed lever 32 above referred to. From the foregoing it will be noted that rotation or oscillation of the nut 26 in a direction to retract the work from the grinding wheel also elevates the arm 51 and consequently the clamp head 48 while a rotation or oscillation of said nut in the opposite direction lowers the pressure head into position for holding the work on the chuck.

Mounted on the housing or slide 24 near its right hand end is a bracket 66 forming a bearing for the work ejector actuating member 67 which has formed in its one end a slot 68 in which is disposed a pin 69 projecting outwardly from the surface of the infeed lever 32. The other end of the member 67 is provided with a trigger 70 adapted to engage with a tooth 71 formed on cam member 72 keyed or otherwise secured to the end of longitudinal shaft 73. The shaft 73 at its inner end has keyed or otherwise secured to it an arm 74 to which is pivoted, as at 75, one end of a link 76. The other end of this link 76 is pivoted as at 77 intermediate the ends of an arm 78 in turn pivoted at 79 to an extending lug 80 of the housing or slide 24. The free end of the arm 78 is provided with a bumper 81 engaging a pusher 82 on the end of ejector rod 83 which passes through the hollow interior of the spindle 37. The inner end of the rod 83 has secured thereto or formed integral therewith a head 84 from which project ejector pins 85 which pass through the chuck 44 and stop short of the inner face of the work 46.

The operation of the mechanism described thus far is as follows: The lever 32, when the work piece is being changed on the chuck, is in a vertical position or considerably to the left of the position shown in Figure 3, with the head or slide retracted or remote from the grinding wheel and with the arm 51 elevated free of the work. A work piece is then mounted on the chuck 44 with the inner end thereof engaging the shoulder 50 whereupon the lever 32 is initially oscillated to the position shown in the drawings, particularly as shown in Figure 3. This effects a rotation of the nut 26 and through the rotation of the pinion 65 secured thereto raises or axially elevates the rack bar 59 to the position shown in Figure 4 which through the flat 58 thereon oscillates the finger 57 and shaft 52 thereby lowering the pressure finger 54 and pressure arm 51 to cause engagement of the pressure plate with the free end of the work. Simultaneously with the centering and clamping of the work the slide or housing 24 is rapidly advanced to the position shown in Figure 5 through the co-operation of the barrel cam 29 and follower 30. From this it will be understood that the cam groove in the barrel cam 29 is provided with a rapid lead for rapidly shifting the work toward the grinding wheel and it should further be noted that the cam groove then has a substantial straight or no lead portion so that after the work and wheel are operatively associated no further movement of the slide is had from the barrel cam 29. After the work and grinding wheel are in engagement the lever 32 is further actuated to complete an arc of substantially ninety degrees (90°) from its initial or vertical position to a horizontal position or with the lever contacting the upper edge of the bed 15. This continued movement of the lever 32 is at a slow rate and rotates the nut 26 for slowly shifting the nut along the screw and thereby slowly feeds the work into the grinding wheel.

The lever 32 is then allowed to remain in its lowered position to permit a sparking out between the work and wheel whereupon the lever 32 is reversed which first retracts the slide 24 to the position shown in Figures 1 and 5 and returns the rack bar 59 to the position shown in Figure 4. Continued return movement of the lever 32 further lowers the rack bar 59 which through the shoulder 61 thereon reversely oscillates the shaft 52 and raises the pressure arm 51 from the work. Simultaneously with this movement the pin 69 on the lever 32 picks up the member 67 and through the trigger 70 oscillates the shaft 73 for shifting the link 76 and ejector arm 78. The movement of the arm 78 is clockwise, as seen in Figure 3, which axially shifts the ejector rod 83 and pins 85 for pushing the work from the

chuck 44. The work is received in a suitable receptacle placed to receive same at the end of the work spindle.

The modification shown in Figures 6 to 11, inclusive, illustrates a semi-automatically operated machine having a modified work supporting chuck mechanism together with means for stopping the rotation of the spindle during the replacement of the work thereon. As shown in Figure 7, the sprocket 38c is mounted on anti-friction bearings 38 so as to normally freely rotate relative to the spindle. The inner end of the sprocket 38c is provided with clutch teeth 87 adapted to intermesh with corresponding clutch teeth formed on the adjacent face of shiftable clutch member 88 splined to the spindle 37. As shown in Figure 7, the clutch teeth are in engagement and the clutch member 88 is provided on the end opposite to the teeth with a brake face adapted to engage with corresponding brake face 90 formed on brake member 91 secured in any desirable manner to the housing or to the spindle bearing bushing 92. In order to axially shift the clutch 88 it is provided with a circumferential groove 93 receiving therein a shipper finger 94 carried by the chuck actuator bar 95. The bar 95 is adapted to be axially shifted through a suitable way provided in the slide or housing 24 and has formed on its one end a notch 96 receiving the ball end of a pivoted lever 97 adapted to engage at its other end with a pusher rod 98 for releasing the cat head clamp 99.

The clamp 99 has projecting from it a rod 100 terminating in engagement with the end of the pusher rod 98. Extending about the clamp rod 100 is a spring 101 engaging on one end with the chuck body 102 and on the other end with an adjustable abutment 103. The chuck body 102 is secured in any desirable manner to the end of the spindle 37 and is therefore immovable and causes the spring 101 to tend to shift the abutment 103 and consequently the clamp rod 100 to the left, as seen in Figure 7. This movement of the head 99 causes the arms 104 and 105 thereof to engage with the tapered or cam nose 106 of the chuck 102 and to open up and engage with the work collet 107 carried by the chuck 102. Movement of the pusher rod 98 to the right through the shifting of the release rod 95 to the left shifts the cat head clamp to the right out of contact with the cam face or nose 106 thereby permitting the spring 108 to oscillate the jaws 104 and 105 toward one another and free the collet 107 whereupon it, together with the work carried thereby, may be removed from the machine so that additional unfinished work pieces may be mounted on the chuck. It will be noted that the clamp was released by shifting the bar 95 to the left which simultaneously disengages the clutch 88 and effects a contact between the braking faces 89 and 90 for stopping the rotation of the spindle during the replacement of the work.

In order to operate the rod 95 it has pivoted to its inner end as at 109 one end of a link 110 the other end of which is pivoted at 111 to a lever 112 carried by a longitudinal rod 113 which is similar in all respects to the rod 73 above described. The rod 113 is operated automatically and terminates in an automatically actuated mechanism enclosed within the housing 114, see Figure 6.

The housing 114 encloses the necessary mechanism for automatically effecting the oscillation

of the shaft 113 and also effects the automatic advancement and retraction of the housing or slide 24 and consequently the work piece carried thereby as respects the grinding wheel. This mechanism comprises a bearing 115 integral with the housing 114 in which is journaled for sliding movement a block 116 in which is mounted for rotative movement a reduced portion 117 of the adjusting screw 25. The reduced portion 117 of the screw extends entirely through the block 116 and also through and beyond the housing 114 to which extending portion is secured a pilot or hand wheel 28. The hand wheel 28 may be rotated for thereby rotating the screw and effecting the adjustment of the housing or slide 24 in the same manner as above described and the said screws may be axially shifted for correspondingly axially shifting the slide or housing 24.

The mechanism for effecting the axial adjustment of the screw 25 comprises a pair of pitmen 118 having their opposite ends respectively coupled or pivoted to the block 116 and bell crank 119. The bell crank 119 in turn is pivoted at the juncture of its arms to the housing and carries at the end of one of its arms a cam follower 120 received in cam groove 121 which is so designed as to effect first a rapid advance of the slide or housing 24 until the work engages the grinding wheel whereupon a slow infeed is effected between the work and wheel, followed by a dwell in the movement of these parts and then a rapid falling away to retract the work from the grinding wheel. The cam 122 is keyed or otherwise secured to a shaft 123 rotatably journaled in a bearing provided by the housing 114 to which is further secured a worm wheel 124 meshing with a worm 125 belted or otherwise connected with a prime mover 126 secured to the housing 114 exteriorly thereof.

From the foregoing it will be noted that the movement of the work is automatic when once mounted on the machine. In order to oscillate the shaft 113 in timed relation with the movement of the carriage 124 the shaft has secured to it interiorly of the housing 114 a single tooth ratchet wheel 127, the tooth 128 of which engages a lug 129 of an axially shiftable rod 130. The rod 130 has a pin and slot connection as at 131 with a lever 132 pivoted at 133 to a lug 134 projecting interiorly of the housing 114. The lever 132 has projecting from it a cam follower 135 adapted to engage with the face cam 122 so as to oscillate the lever 132 in timed relation with the rotation of the cam 122.

In order to automatically eject the work and collet 107 from the chuck 102, the said chuck has loosely mounted therein for axial movement relative thereto a plurality of ejector pins 137. The ejector pins 137 each have formed on its inner end a head 138 adapted to be engaged by the flange 139 of spring cup 140. The spring cup 140 forms part of the spring abutment 103 and therefore moves with the clamp head rod 140 100 when the said rod is moved to release the work. As will be seen from the drawings, lost motion is provided between the heads 138 of the pins 137 and the flange 139 so that the clamp head 99 is free of the work before the 145 ejector pins engage same and eject it from the chuck.

In view of the foregoing description of the operation of the manually operated machine, it is believed that the operation of the semi-auto-

matic modification thereof will be evident without a further description thereof. It should, however, be noted that after a work piece is mounted on the chuck it is first automatically centered and then clamped in position whereupon the work is automatically advanced to the grinding wheel, fed relative thereto, retracted therefrom, and then released to permit a replacement of the work, whereupon the cycle is repeated.

What is claimed is:

1. In a grinding machine of the class described the combination of a bed, a grinding wheel rotatably mounted thereon, a work rotatable spindle rotatably mounted on the bed for movement toward and from the grinding wheel, a support for the work rotating spindle, a chuck on said work rotating spindle for receiving a work piece, means on the support for engaging the work to hold same on the chuck during the grinding operation, means for actuating the support relative to the bed to effect a feed between the work and grinding wheel, and means co-ordinating the movement of the work holding means and work feeding means whereby they are operated in sequential order.

2. In a grinding machine of the class described the combination with a bed, of a grinding wheel rotatably mounted thereon, a work supporting and feeding unit comprising a support mounted on the bed for movement relative thereto toward and from the grinding wheel, a chuck on the support for receiving thereon the work to be operated upon, an oscillatable arm adapted to engage the free end of the work to hold the same on the chuck, means for oscillating the arm toward and from the work, and means operable to eject the work from the chuck when the arm is raised out of contact with the work.

3. In a grinding machine of the class described the combination with a bed, of a grinding wheel rotatably mounted thereon, a work supporting and feeding unit comprising a support mounted on the bed for movement relative thereto toward and from the grinding wheel, a chuck on the support for receiving thereon the work to be operated upon, an oscillatable arm adapted to engage the free end of the work to hold same on the chuck, means for oscillating the arm toward and from the work, means operable to eject the work from the chuck when the arm is raised out of contact with the work, and means synchronizing the movement of the ejector and arm whereby the ejector is not operated until the arm is free of the work.

4. In a grinding machine of the class described the combination with a bed, of a grinding wheel rotatably mounted thereon, a work supporting and feeding unit comprising a support mounted on the bed for movement relative thereto toward and from the grinding wheel, a chuck on the support for receiving thereon the work to be operated upon, an oscillatable arm adapted to engage the free end of the work to hold same on the chuck, means for oscillating the arm toward and from the work, means operable to eject the work from the chuck when the arm is raised out of contact with the work, means synchronizing the movement of the ejector and arm whereby the ejector is not operated until the arm is free of the work, means for effecting the movement of the work support toward and from the grinding wheel, and means synchronizing the movement of the work

support with the movement of the work holding arm and ejecting means.

5. In a grinding machine of the class described for producing exterior surfaces of revolution on hollow work pieces the combination with a bed, and a grinding wheel rotatably mounted on said bed, of a work supporting and feeding unit comprising a support on the bed, a work rotation spindle rotatably journaled in the support, a chuck associated with the spindle and received in the bore of the work, clamping means engaging the outer end of the work to hold same on the chuck, means for feeding the work support toward the grinding wheel while the work is clamped on the chuck, and means for ejecting the work from the chuck.

6. In a grinding machine of the class described for producing exterior surfaces of revolution on hollow work pieces the combination with a bed, and a grinding wheel rotatably mounted on said bed, of a work supporting and feeding unit comprising a support on the bed, a work rotation spindle rotatably journaled in the support, a chuck associated with the spindle and received in the bore of the work, clamping means engaging the outer end of the work to hold the same on the chuck, means for feeding the work support toward the grinding wheel while the work is clamped on the chuck, means for ejecting the work from the chuck, and means synchronizing the movement of the support with the clamping and unclamping of the work as well as with the actuation of the ejector.

7. In a grinding machine of the class described for producing exterior surface of revolution on hollow work pieces the combination with a bed, and a grinding wheel rotatably mounted on said bed, of a work supporting and feeding unit comprising a support on the bed, a work rotation spindle rotatably journaled in the support, a chuck associated with the spindle and received in the bore of the work, clamping means engaging the outer end of the work to hold same on the chuck, means for feeding the work support toward the grinding wheel while the work is clamped on the chuck, means for ejecting the work from the chuck, and means synchronizing the movement of the support with the clamping and unclamping of the work as well as with the actuation of the ejector, and means for stopping the rotation of the chuck prior to the ejection of the work therefrom.

8. In a grinding machine of the class described for producing exterior surface of revolution on hollow work pieces the combination with a bed, and a grinding wheel rotatably mounted on said bed, of a work supporting and feeding unit comprising a support on the bed, a work rotation spindle rotatably journaled in the support, a chuck associated with the spindle and received in the bore of the work, clamping means engaging the outer end of the work to hold same on the chuck, means for feeding the work support toward the grinding wheel while the work is clamped on the chuck, means for ejecting the work from the chuck, said clamping means comprising a member adapted to engage the free end of the work, yielding means for holding said clamping member in engagement with the work, and positively actuated means for rendering said yielding means inoperative and releasing the work.

9. In a mechanism for supporting and rotating hollow work pieces for presentation to a grinding wheel the combination of a bed, a
